UNITED STATES PATENT OFFICE

168,966

ORNAMENT FOR AN AUTOMOBILE BODY

Harold W. Pilkey, Detroit, Mich., assignor to Chrysler Corporation, Highland Park, Mich., a corporation of Delaware

Application June 11, 1952, Serial No. 30,120

Term of patent 7 years

(Cl. D14—6)

To all whom it may concern:

Be it known that I, Harold W. Pilkey, a citizen of the United States, residing in the city of Detroit, county of Wayne, and State of Michigan, have invented a new, original, and ornamental Design for an Ornament for an Automobile Body, of which the following is a specification, reference being had to the accompanying drawing, forming part thereof, in which:

Fig. 1 is a front elevational view of an ornament for an automobile body, showing my new design;

Fig. 2 is a top plan view thereof;

Fig. 3 is a side elevational view thereof;

Figs. 4 and 5 are sectional views taken on the lines 4—4 and 5—5 of Fig. 1; and

Fig. 6 is a perspective view thereof wherein the broken lines indicating an automobile are for illustrative purposes only.

I claim:

The ornamental design for an ornament for an automobile body, substantially as shown.

HAROLD W. PILKEY.
